United States Patent Office

Des. 179,145
Patented Nov. 6, 1956

179,145

SERVICE T

Frank H. Mueller, Decatur, Ill., assignor to Mueller Co.,
Decatur, Ill., a corporation of Illinois

Application February 1, 1955, Serial No. 34,312

Term of patent 14 years

(Cl. D91—3)

FIG. 1.

FIG. 2.

FIG. 3.

The essential features of the design reside in the portions shown in full lines.

I claim:

The ornamental design for a service T substantially as shown and described.
